UNITED STATES PATENT OFFICE.

GEORGE E. GODDARD, OF DETROIT, MICHIGAN, ASSIGNOR TO PACKARD MOTOR CAR COMPANY, OF DETROIT, MICHIGAN, A CORPORATION OF MICHIGAN.

WINDSHIELD.

Application filed January 28, 1916. Serial No. 74,871.

To all whom it may concern:

Be it known that I, GEORGE E. GODDARD, a citizen of the United States, and resident of Detroit, county of Wayne, State of Michigan, have invented certain new and useful Improvements in Windshields, of which the following is a specification.

This invention relates to windshield construction and has for one of its objects the provision of a windshield embodying features especially adapted for use in connection with enclosed bodies to exclude air and dust when the swinging sash of the windshield is in the closed position. A further object is to provide an improved form of trunnion connection between the swinging sash and the frame. A further object is to provide an improved form of clamping means for securing the swinging sash in its different positions.

Other objects and the features of novelty will be apparent from the following description taken in connection with the accompanying drawings, in which:—

Figure 1 is a front elevation of one side of a windshield for an enclosed body, the construction embodying my invention.

Figure 2 is a longitudinal section substantially on the line 2—2 of Figure 1.

Figure 3 is a transverse section on the line 3—3 of Figure 1.

Figure 4 is a vertical section on the line 4—4 of Figure 1.

Figure 5 is an enlarged vertical section on the line 5—5 of Figure 2.

Figure 6 is an enlarged section on the line 6—6 of Figure 1.

Figure 7 is an enlarged section on the line 7—7 of Figure 1; and

Figure 8 is a section similar to Figure 4 and showing a modification.

Referring to the drawings, 10 indicates any suitable form of supporting structure, the design of which will vary with the type of body with which the improvements described hereinafter are employed. The frame 10 has secured therein a lower sash 11 which is preferably stationary and in order to secure the sash 11 an angle member 12 is arranged on the frame 10 and secured thereto in any suitable manner as by means of screws 13 (see Figure 7). The glass 14 is secured in the sash 11 by means of a suitable filler 15. Screws 16 secure the sash 11 to the angle member 12. In order

to provide an air-tight joint between the sash 11 and the frame 10, the former has projecting from its opposite side edges and also preferably from the bottom edge flanges 17 which overlap the frame 10. A groove 18 is arranged at the root of the flanges 17 and in this groove a packing formed preferably of tubing 19 of rubber or other flexible material. The tubing 19 has arranged therein a wire or cord 20 which is pressed into the groove with the tubing and secures the latter. In assembling the parts the material of the tubing yields sufficiently to permit the wire with the surrounding portion of tubing to be forced through the space between the ridges 21 and 22 at the mouth of the groove 18.

As clearly shown in Figure 7 the tubing 19 cooperates with the frame 10 and the flanges 17 so as to form a tight joint therebetween which will exclude dust as well as air. The joint is of such a character, however, that the sash 11 may be readily removed and replaced without destroying any of the parts of the joint.

The swinging sash 23 which encloses the glass panel 24 is arranged above the sash 11 so that its lower edge cooperates with the upper edge of the latter, a tight joint being formed between these edges, when the upper sash is closed, by means of a flange 25 on the sash 23 and a tubular packing 26 which engages with the sash 11, this packing being preferably similar to the packing 19 and may be constructed and secured to the sash 23 in the same manner that the packing 19 is secured to the sash 11. An alternative to this construction is shown in Figure 8 in which the sash 27 has a flange 28 adapted to overlap the operating frame 29. To the latter frame, which is preferably stationary there is secured a tubing 30 which may be similar to the tubing 19 and which may be secured to the frame 29 in any suitable manner as by means of a metallic strip 31 which is formed with a grooved portion 32 in which the wire 33 and one edge of the tubing are inserted.

Referring to Figures 5 and 6 it will be observed that the frame 10 has secured thereto by means of screws 34 a cup-shaped member 35, the cup of this member being arranged adjacent the upper edge of sash 23 but slightly below the same. It will be understood that at the opposite side of the

sash 23 the frame 10 will have another member similar to the member 35 and projecting toward the sash 23. The sash 23 has secured adjacent its upper corners cup-shaped members 36 which telescope within the members 35 to form trunnion connections between the sash and the frame 10. Surrounding the cup 37 of the member 35 is a flexible band 38, one end of which is 5 anchored to the member 36 as indicated at 39, the other end of the band 38 being formed with an abutment 40 and arranged in the recess 41 in the member 36, as shown in Figure 2. A screw 42, carried by the member 36, engages the abutment 40 for the purpose of clamping the band 38 against the outer surface of the cup 37.

Referring to Figure 3 it will be observed that the sash 23 has a laterally projecting flange 43 along one of its sides and it will be understood that the opposite side of the sash is provided with a similar flange. A tubular packing 44 which preferably corresponds in construction and arrangement to the packing 19, is provided on the inner side of the flange 43 and is adapted to engage the frame 10 to provide a tight joint. The arrangement of the parts thus far described is such that when the screws 42 at the upper 20 corners of the sash 23 are turned to tighten the clamps 38, in securing the sash 23 in its closed position, the sash will be drawn toward the frame 10 and thus compress the packing along the edges of the sash more 25 tightly and also eliminate any tendency for the sash to rattle.

An open position of the sash 23 is indicated by the broken lines 45 in Figure 2 and on account of the axis of the trunnions of 40 the sash being below the upper edge of the latter, the upper edge will swing inwardly when the sash is swung to an open position. In order to form a closure between the upper edge of the sash and the frame 10 when 45 the sash is open as well as when it is closed and also permit the required movement of the sash, there is secured to the inner side of the frame 10 a strip of flexible material 46 which has a fold 47 between the upper edge 50 of the sash and the frame 10 and is secured along the inner corner of the sash as indicated at 48. The strip 46 may be of leather or fabric and is secured to the sash by a wire 49 which is arranged in a hem in 55 the strip. In order to provide a neat finish on the inner side of the frame 10 and conceal the hem in the material 46 a flange 49 projects upwardly from the sash 23. It will be evident that the fold 47, not being secured 60 along the edge 50 of the frame 10, will permit the sash to be swung freely to and from its open positions. The sash may be conveniently opened and closed by suitable handles 51 arranged preferably adjacent the 65 lower corners thereof.

Having thus described the invention, what is claimed and desired to be secured by Letters Patent is:

1. In a windshield for vehicles, the combination of a frame, a sash arranged in said frame, telescopic members on the sash and frame cooperating to form trunnions on which the sash is adapted to swing in the frame, flexible means between the edges of the sash and the frame adapted to prevent the passage of air when the sash is closed and means cooperating with said trunnions to secure the sash in different positions and adapted to compress said flexible means when securing the sash in its closed position. 70

2. In a windshield for vehicles, the combination of a frame, a sash pivotally connected with the frame and adapted to swing to different positions therein, flexible means between the edges of the sash and said frame and adapted to form an air-tight joint and clamping means cooperating with the pivotal connections of the sash to secure the latter in its different positions, said clamping means being adapted to compress said flexible means in securing the sash in its closed position. 80

3. In a windshield for vehicles, the combination of a rectangular sash pivotally mounted in said frame and adapted to swing to different positions therein, flanges projecting from three sides of the sash into overlapping relation with the frame, flexible packing between said flange and the frame, means forming an air-tight connection between the fourth side of the sash and the frame and clamping means for securing the sash in different positions adapted to draw said flanges toward the frame when securing the sash in its closed position. 100

4. In a device of the class described, the combination of a frame, a sash arranged therein, a cup-shaped member secured to said frame, a cup-shaped member secured to said sash and telescoping within the first mentioned cup-shaped member to form a trunnion connection between the sash and frame, a flexible band surrounding the first mentioned cup-shaped member and having its ends anchored to the second mentioned 110 cup-shaped member and a screw on the latter member for controlling said band. 115

5. In a device of the class described, the combination of a support, a member arranged to swing on said support and a pivotal connection between the support and member comprising cooperating telescoping parts on the support and member, the part on the member being within the part on the support, a flexible band surrounding the part on the support and having its ends anchored to the part on the member and means carried by said member for controlling said band. 120

6. In a device of the class described, the 130

combination of a support, a member arranged to swing thereon and a trunnion connection between the support and member comprising telescoping parts, the part on said member engaging the interior of the part on said support, a flexible band surrounding the part on said support and having one end anchored to said member and a screw carried by said member and cooperating with the opposite end of the band to control the clamping action thereof. In testimony whereof I affix my signature.

GEORGE E. GODDARD.
